SPRING CLIP FABRIC AMMUNITION BELT

Guy T. Bixby, Dayton, Ohio

Application August 19, 1944, Serial No. 550,295

8 Claims. (Cl. 89—35)

(Granted under the act of March 3, 1883, as amended April 30, 1928, 370 O. G. 757)

1.

The invention described herein may be manufactured and used by or for the Government for governmental purposes, without the payment to me of any royalty thereon.

This invention relates to ammunition belts and is particularly concerned with an improvement in fabric or woven ammunition belts although it also has application in other types of belts in which difficulty is encountered in adequately gripping the cartridges.

Fabric ammunition belts woven from vegetable fiber and provided with pockets for receiving individual rounds of ammunition have proved themselves to be of considerable worth and exceedingly efficient in certain types of operations and applications. However, belts of this type have not been highly successful for use in aircraft machine gun installations for a plurality of reasons including their inability to uniformly clasp and hold the individual cartridges with the correct degree of firmness, a feature which is accentuated by rapid change in a plane's course or speed. Factors contributing primarily to this inability to consistently appropriately grip the cartridges are two characteristics of the fabric belt which have heretofore been considered to be inherent therein, namely, inability to provide, in manufacture, precision uniformity in the size of the numerous cartridge pockets and shrinkage of the belt when atmospheric conditions are highly humid or the belt has become appreciably damp from other cause.

As will be obvious, variation in the size of the ammunition pockets means variation in the firmness of the grip with which the various pockets hold the respective rounds of ammunition so that in a particular belt some pockets may hold the cartridges with precisely the desired amount of cleavage whereas others may hold their cartridges too firmly for the extraction facilities provided in the gun and still others may fail to exert a sufficient grip upon the cartridges to retain them in their proper positions in the belt.

With respect to the effect of the belt's becoming saturated, or partially saturated, such a condition frequently causes a belt which normally holds the cartridges with approximately the desired degree of firmness to grip them with such tenacity that extraction from the belt is substantially impossible with the facilities normally provided for the operation.

It is an object of this invention to provide a fabric belt in which the successive rounds of ammunition are each gripped with substantially the same degree of firmness.

2.

Another object of this invention is to provide a fabric belt which grips the cartridges with substantially the same degree of tenacity when wet as when dry.

5. Another object of my invention is to provide an ammunition belt of the fabric type which is adapted to grip rounds of ammunition sufficiently accurately to enable its use in aircraft machine gun installations.

10. Still another object of this invention is to teach ammunition belt construction which is adapted to provide substantially uniform cartridge grip in a belt otherwise lacking in this regard.

Yet a further object of my invention is to provide a novel process for assembling a belt which embodies my preferred construction.

In its preferred form my invention comprises a standard fabric ammunition belt having spaced pockets for receiving individual rounds of ammunition, said pockets being restricted in the sections which receive the necks or small diameter portions of the cartridges. Encircling these restricted neck portions of the pockets, spring rings are provided which, in a simple form, comprise strands of spring metal formed into generally circular rings having their respective ends overlapping each other. The said spring rings are so sized or dimensioned as to snugly press the adjacent portions of the neck sections of the pockets against the respective cartridge necks whereby the said cartridges are held in the secure grips of the said spring rings.

In order that a clear and concise explanation of my invention may be given, reference is made to the accompanying drawings forming a part of this specification, in which:

Figure 1 is a fragmentary perspective view of a cartridge belt fabricated in accordance with the preferred form of my invention, a cartridge being shown in place in one of the pockets of said belt;

Figure 2 is a longitudinal sectional view taken on the line 2—2 of Figure 3;

Figure 3 is a transverse sectional view taken on the line 3—3 of Figure 2;

Figure 4 is a detailed perspective view of one of the spring wire rings or clips incorporated in the construction shown in Figure 1; and

Figure 5 is a detailed perspective view of a modified form of ring.

Referring now more specifically to the drawing and especially to Figures 1 and 2 thereof, the belt body has been designated generally by the reference character 10 and comprises a plurality of runs or strips 11 and 12 of web fabric attached

as at 13, to one another at spaced intervals to provide pockets 14 adapted to receive the body portion 15 of the cartridge 16. Restricted sections 17 of the pockets 13 are provided by attaching the runs 11 and 12 to one another at junctures 5 18 which are spaced a lesser distance apart than are the attachment means 13. The means for fastening the strips or runs of web together may, of course, be of any suitable nature such, for example, as crossing and/or interweaving; the said 10 runs may even be sewed together. On the other hand the belt body may comprise a single relatively thick web having pockets woven or cut therein.

The belt body thus far described is well known in the art and has been illustrated by me here for the purpose of demonstrating a preferred embodiment of my invention. The spring rings 19 shown in the drawing each comprises a single strand of spring wire formed into general ring shape and having its ends 20 and 21 overlapping for an appreciable distance. Inspection of Figure 1 discloses that the said spring rings 19 are disposed adjacent and about the neck portions 17 of the pockets of the belt penetrating the runs 11 and 12 at two points, namely, approximately coincident with the two fastening junctures 18 bounding the respective necks 17, so that a portion of each said ring is disposed on one side of the web runs 11 and 12 and another portion thereof is disposed on the other side of said runs.

Each ring 19 is so dimensioned with relation to the size of the neck of the particular caliber and style of cartridge which the belt of which said ring is a part is designed to receive that it exerts a substantial gripping effect upon said cartridge neck when the thicknesses of the portions of the webs 11 and 12 comprising the restricted pocket section 17 are disposed between said ring and said cartridge neck in the manner illustrated in Figure 1.

All of the rings 19 being formed to the same size, it will be apparent that the tenacity of the grip exerted upon each of the successive cartridges is substantially uniform regardless of the precise sizes of the respective pockets. Also, the compression grip or modulus of resistance to deflection of said metal spring rings 19 being substantially unaffected by humidity it is possible to prepare the belt of my invention so that the grip or cleavage exerted upon the cartridges is substantially constant whether the belt is wet or dry. This latter effect is secured by providing pockets of a size such that even when shrunk they do not cling excessively to the cartridges.

The novel process which I have conceived for preparing my belt comprises the steps of preparing the fabric or web body portion including the pockets 14, with the restricted sections 17, in any suitable manner, providing orifices through the belt on each side of each of the restricted or neck pocket sections, as with an awl, and threading the rings 19 through the orifices thus provided, either in a preformed condition or prior to having been pressed into their final forms. In the latter event each of said rings is, of course, preferably given the general configuration of a ring after being threaded into the aforesaid orifices of the belt.

The modified ring illustrated in Figure 5 is provided with a sharpened end 20a which enables installation of the ring in the belt body without the prior preparation of orifices for receiving said ring. The sharpened end is employed as a needle point to itself pierce the webbing of the body of the belt, first on one side and then on the other

side of the neck section of the pocket as the ring is rotated to effect its complete installation in the belt body in a manner which will be clearly apparent. If desired both ends of the ring may be formed with points.

While desirable from certain standpoints, the provision of sharpened ends, or even a sharpened end, on each ring is somewhat hazardous from the standpoint of danger to the operator of the gun using the belt.

A further modification exemplified in the ring shown in Figure 5 comprises the laterally disposed prongs or barbs 22 and 23 which serve to positively locate the ring in the belt after it has been installed. As will be evident from scrutiny of the drawing, the said barbs as shown serve to engage a surface of the belt body 10 to prevent rotation of the ring in either direction. If desired the number of such prongs may be varied.

While I have found the simple metallic spring ring shown in detail in the drawing to be entirely adequate and while it is highly efficient from the standpoints of simplicity of preparation and cost, it may, of course, be replaced by other types of inserts adapted to perform the same general function; for example, elastic may be employed as may also other suitably resilient material. Even a substantially rigid closed ring may be used with an appreciable degree of satisfaction; in that case the cartridge is held primarily due to friction resulting from a tight fit. If a resilient metal ring or other form of resilient metal insert be employed it may, obviously vary substantially from ring 19 shown for illustrative purposes.

My invention is, of course, in no way limited to a particular construction for the web body portion of the belt and the point at which the resilient insert is applied may be greatly varied. For example, it may be so disposed as to grip the body of the cartridge rather than the neck thereof and/or it may be arranged within the belt pocket so that it directly engages the cartridge.

While I have described my invention as particularly applicable to fabric belts formed from vegetable fiber, it may be employed with belts formed of other types of fiber and it may even be used in connection with belts which are not of the web type at all, in which difficulty in correctly and consistently gripping the cartridges is experienced.

Although the foregoing discourse has been devoted to description of certain specific embodiments of my invention, together with several modifications thereof, in order to provide a clear teaching of my invention and my novel process for preparing the preferred form thereof, it is clear that numerous additional modifications and eliminations will occur to one skilled in the art, and this without departing from the spirit and scope of my invention. It is therefore desired to be limited herein only by the prior art and the appended claims.

I claim:

1. An ammunition belt comprising a body having a plurality of fabric cartridge-receiving means including a plurality of cartridge pockets each having a longitudinal axis, and a plurality of separate spring rings, one for each cartridge pocket, anchored to said body and constructed and arranged to encircle each said cartridge pocket in a plane normal to said longitudinal axis to at least indirectly and individually grip cartridges disposed in said receiving means.

2. An ammunition belt comprising a body having a fabric cartridge-receiving means including

a cartridge pocket having a longitudinal axis, said cartridge pocket being provided with a restricted coaxial portion generally conforming to the neck portion of a cartridge to be carried thereby, and a spring ring anchored to said body and encircling the exterior of the restricted portion of said cartridge pocket normal to the longitudinal axis thereof to resiliently reinforce said restricted portion for increasing the gripping action thereof on a cartridge.

3. An ammunition belt comprising a fabric body having a fabric cartridge-receiving means including a cartridge pocket having a longitudinal axis, and a disjoined or discontinuous spring ring, having at least one of its ends sharpened and passed through said body and constructed and arranged to encircle said cartridge pocket in a plane normal to said longitudinal axis thereof for indirectly gripping a cartridge disposed in said receiving means.

4. An ammunition belt comprising a body having a fabric cartridge-receiving means including a cartridge pocket having a longitudinal axis, a disjoined or discontinuous spring ring passed through said body and constructed and arranged to encircle said cartridge pocket in a plane normal to said longitudinal axis thereof for indirectly gripping a cartridge disposed in said receiving means, and a protuberance on said spring ring engaging said body for locating said spring ring.

5. An ammunition belt comprising a body having a fabric cartridge-receiving means including a cartridge pocket having a longitudinal axis, and auxiliary gripping means connected to said body and positioned exteriorly of said cartridge pocket in a plane normal to said longitudinal axis and constructed and arranged to exert a resilient restricting action on said cartridge pocket to increase the effectiveness of said receiving means to grip a cartridge disposed therein.

6. An ammunition belt comprising a body having a fabric cartridge-receiving means including a cartridge pocket having a longitudinal axis, said cartridge pocket being provided with a coaxial restricted section generally conforming to the contour of the neck of a cartridge to be carried thereby, and auxiliary gripping means connected to said body and positioned exteriorly of the restricted section of said cartridge pocket normal to the longitudinal axis thereof and constructed and arranged to exert a resilient con-

fining action on said restricted section to increase the effectiveness of said restricted section to grip a cartridge disposed in said receiving means.

5 7. In an ammunition belt, a plurality of receiving means for cartridges including a plurality of cartridge pockets having parallel longitudinal axes, the inherent constructions of which cartridge pockets are such that they lack ability to at all times maintain uniformly correct control over the positions of the cartridges received thereby, and a plurality of individual auxiliary stabilizer means, one for each receiving means, connected to said belt and encircling each said cartridge pocket normal to the respective longitudinal axis thereof and constructed of relatively stiff but resilient material and arranged to exert a confining pressure on said respective cartridge pockets for affecting the positions of cartridges carried thereby.

10 8. In an ammunition belt, a plurality of receiving means for cartridges including a plurality of cartridge pockets having parallel longitudinal axes, the inherent constructions of which cartridge pockets are such that they lack ability to at all times maintain uniformly correct control over the positions of the cartridges received by them, and a plurality of individual auxiliary spring rings, one for each receiving means, connected to said belt and encircling each said cartridge pocket normal to the respective longitudinal axis thereof, constructed of relatively stiff but resilient material and arranged to exert a confining pressure on said respective cartridge pockets to indirectly grip cartridges carried thereby.
